Primary Examiner — Garth Rademaker*Assistant Examiner* — Laura H Yu(74) *Attorney, Agent, or Firm* — Barry Choobin; Patent 360(57) **CLAIM**

The ornamental design for a 3-dimensional identification card, as shown and described.

DESCRIPTION

FIG. 1 is a perspective view of a 3-dimensional identification card, showing my new design;
 FIG. 2 is a front view thereof;
 FIG. 3 is a rear view thereof;
 FIG. 4 is a right side view thereof;
 FIG. 5 is a left side view thereof;
 FIG. 6 is a top view thereof; and,
 FIG. 7 is a bottom view thereof.

The broken lines depict portions of the 3-dimensional identification card that form no part of the claimed design.
